15 Claims. (Cl. 235—61)

1

This invention relates generally to a computer and more in particular to the electrical analogy type of computer.

In certain of its aspects this invention is related to U. S. Patent 2,420,891, G. D. McCann, Jr. et al., granted May 20, 1947 and assigned to the same assignee as this invention.

The use of electrical analogy types of computers in the study of various physical problems has been known for the past several years. The use of such a computer system in the study of steady state conditions in power systems has been applied fairly extensively and in recent years through the development of suitable excitation means for the analogy circuits such studies have been extended to transient problems not only in the power transmission field mentioned but also in other fields, more importantly among these being in the study of mechanical and electro-mechanical systems.

For the purposes of this disclosure, and without any intention of limiting the scope of the teachings hereof, the discussions hereinafter presented will be concerned with the study of transient problems in turbine generator systems. For instance, the determination of shaft torques upon synchronization of such generators out of phase or on the occurrence of short circuit.

The characteristics of the air gap torques occurring when such generators are synchronized out of phase or upon the occurrence of a short circuit are well known and may include damped unidirectional components, sinusoidal components of fundamental frequency and of harmonic frequencies, as well as cosine components. The development of suitable excitation circuits for producing voltages corresponding to these various components are well covered in the above-mentioned patent of G. D. McCann, et al., and this invention is directed primarily to an improved method and apparatus for producing cosine voltages in excitation systems of the character mentioned.

Generally, it is an object of this invention to provide an improved type of electrical analogy computer.

A further general object of this invention is to provide an improved type of excitation circuit for use in an electrical analogy type of computer.

More specifically stated, it is an object of this invention to provide an excitation circuit for an electrical analogy type of computer embodying improved means for producing cosine voltages.

The foregoing statements are merely illustra-

tive of the various aims and objects of this invention. Other objects and advantages will become apparent upon a study of the following disclosure when considered in conjunction with the accompanying drawings, in which:

Fig. 1 diagrammatically illustrates an electrical analogy type of computer having an excitation circuit for producing sine voltages.

Fig. 2 is a graph illustrating a typical form of decaying amplitude sine voltage produced in the excitation network of Fig. 1.

Fig. 3 diagrammatically illustrates an electrical analogy type of computer having an exciting circuit for producing sine and cosine voltages of decaying amplitude.

Fig. 4 is a graph of typical sine and cosine voltages produced in the excitation network of Fig. 3.

Fig. 5 is a diagrammatic showing of an electrical analogy computer having an excitation network embodying the principles of this invention.

Fig. 6 is a similar type of computer having an excitation network which is a variation of that shown in Fig. 5, and

25 Figs. 7, 8 and 9 demonstrate the application of this invention in the solution of a typical generator torque problem.

In Figs. 1 and 3 of the drawings typical computer networks are illustrated of a type disclosed 30 and claimed in U. S. Patent 2,420,891, issued May 20, 1947 and assigned to the same assignee as this invention. The circuits of Figs. 1 and 3 and their respective characteristic curves in Figs. 2 and 4 are herein illustrated and discussed that 35 the improvements afforded by this invention may be more readily understood.

In the study of most transient problems the cathode ray oscilloscope usually affords the best 40 means of measuring the quantities which are to be determined. Since this oscilloscope is primarily a voltage measuring instrument, a frequently convenient analogy is that in which the desired force or torque in the mechanical system is proportional to a voltage in the electrical 45 analogy circuit. In other analogies the current can just as readily be measured by taking a voltage drop across a resistor element in the analogy circuit. Thus the mass capacitance analogy might also be used.

50 The analogy circuit of Fig. 1 is based upon the mass-inductance analogy and represents a simple three-mass system. For instance, that represented by a generator and two turbines for driving the generator connected along a common shaft in which case the inductor $1L$ is propor-

tional to the mass of the generator, the inductor $2L$ is proportional to the mass of the first turbine and the inductor $3L$ is proportional to the mass of the second turbine. The capacitors $1C$ and $2C$, connected in parallel in the analogy network, are each inversely proportional to the spring constants of the shaft sections between the generator and the first turbine and the first and second turbines respectively. The voltages appearing across the respective capacitors $1C$ and $2C$ upon the application of suitable excitation voltages to the analogy network are therefore proportional to the peak stresses occurring in the shaft for a given operating condition and may be conveniently observed upon the screen of a cathode ray oscilloscope designated CRO in the drawing, selectively connected to measure the voltages across the respective capacitors. Switches SS_6 and SS_7 respectively connected in series with resistors R_6 and R_7 across capacitors $1C$ and $2C$ are provided to remove energy from the analogy circuit during intervals between the applications of excitation thereto as will be described more fully in connection with Fig. 9.

The excitation circuit in this case has not been set up to represent any specific problem but is one which will produce sinusoidal voltages of decaying amplitude of a type typically representative of the components of air gap torque occurring in the generator upon short-circuit or upon synchronization out of phase. Each component of torque is represented in a voltage produced in an oscillator network in the excitation circuit. Four of these oscillator circuits are shown. These may produce voltages of various amplitude and of the same frequency or various frequencies depending upon the character of the particular quantities which are to be electrically reproduced. For instance, the first oscillator circuit comprising the capacitor C_1 , inductor L_1 and resistor R_1 may produce a voltage of given amplitude and of fundamental frequency. The second oscillator circuit including the capacitor C_2 , the inductor L_2 and the resistor R_2 may produce a voltage of some harmonic frequency, for instance, the second harmonic. The third oscillator circuit including the capacitor C_3 , the inductor L_3 and resistor R_3 may produce a voltage of fundamental frequency but of opposite sense to that of the first oscillator circuit and similarly the fourth oscillator circuit including capacitor C_4 , inductor L_4 and resistor R_4 may produce a voltage of the second harmonic frequency but of opposite sense to that of the second oscillator circuit. The foregoing discussion is merely illustrative of the combinations which may be effected. It will be appreciated that each of the circuits above described may be of different frequencies and of various voltage magnitudes or may all be of the same frequency and various voltage magnitudes etc., depending upon the requirements. Each oscillator circuit includes a portion of the resistor R and a common leg for each oscillator circuit is formed by the synchronous switch SS which operates to simultaneously open and close the oscillator circuits at a speed which is commensurate with the time constants of the respective circuits and also of a speed to afford persistency of the image being viewed upon the screen of the cathode ray oscilloscope so as to afford a standing reproduction of the transient phenomena being observed.

The oscillator circuits are each connected to a charging circuit having a battery B as the common source of charging potential. Each charg-

ing circuit is connected across the corresponding one of capacitors C_1 , C_2 , C_3 and C_4 and each charging circuit includes the corresponding one of resistors R_1 through R_4 which controls the charging current in the particular circuit. Each of these resistors R_1 through R_4 is of sufficient magnitude that the charging circuit is effectively isolated by the resistance thereof from the corresponding oscillator circuit when the synchronous switch SS closes the common leg of the oscillator circuits and also of such size as to permit the capacitors to become essentially fully charged during the period when the switch SS is open. Thus the stored energy in each of the capacitors in the oscillator circuits is released in the oscillator circuit and the circuits oscillate after closing of the synchronous switch substantially independently of the charging circuit associated therewith.

The particular turbine system under consideration is a low loss mechanical system. Thus the analogy circuit must be a low loss electrical system. This is accomplished by utilizing high Q coils in the analogy circuit and in general keeping the analogy circuit resistance low. For this reason in the particular type of circuit being considered the value of the resistor R as well as other components in the oscillator circuits of the network must be kept as low as possible so that the internal impedance of the excitation network as viewed from the analogy network is a minimum, that interference with the analogy network for all practical purposes will be negligible. The resistors R_1 through R_4 may be actual physical resistors added in series in the various oscillator circuits or may represent only the lumped resistance of each oscillator circuit due to the resistive properties of the inductors and capacitors therein. Synchronous switches SS_6 and SS_7 and their respective series resistors are respectively connected across the capacitors $1C$ and $2C$ of the analogy circuit. Physically these switches are connected mechanically with switch SS and operated therewith. The setting is such that upon closure of switch SS to initiate oscillation in the excitation circuits switches SS_6 and SS_7 are opened. When switch SS opens to initiate charging in the excitation circuits switches SS_6 and SS_7 close and short circuit the components of the analogy circuit and remove the residual electrical energy therefrom placing these circuits at rest in advance of the reapplication of excitation across resistor R .

In Fig. 3, for the purpose of simplifying the illustration, the analogy circuit is represented in the form of a block. The excitation circuit of Fig. 3 is similar to that of Fig. 1 but in addition incorporates means for producing cosine voltages as well as sine voltages as generally characterized by the graph of Fig. 4. The circuits in Fig. 3 involving the inductor L_1 , capacitor C_1 , resistor R_1 , inductor L_3 , capacitor C_3 and resistor R_3 are the same as those bearing the same reference characters illustrated in Fig. 1 and the operation thereof will be understood in connection with the discussion concerning Fig. 1.

The cosine voltages are produced in this instance across the inductors $2L$ and $4L$, now forming a part of the impedance Z corresponding to resistor R of Figure 1 in which the various oscillator voltages are accumulated to produce the total voltage corresponding to total air gap torque. One oscillator circuit for producing the cosine voltages includes the capacitor C_2 , inductor L_2 and resistor R_2 and this circuit is

connected along a tapped portion of the inductor $2L$. A circuit for producing a cosine function of opposite sense includes the capacitor $C4$, inductor $L4$ and the resistor $R4$ and this circuit includes a tapped portion of the inductor $4L$ forming a part of the impedance in which the oscillator voltages are combined. These circuits, it will be appreciated, may produce various relative magnitudes of voltages and various frequencies or the same frequency as the particular circumstances require, and each is charged by means of its charging circuit connecting the capacitor therein across the battery B . Upon charging of the capacitors in the oscillator circuits in Fig. 3, closure of the synchronous switch $SS1$ results in a discharge of these capacitors into the various oscillator circuits and since the voltage appearing across the two inductors $2L$ and $4L$ of impedance Z is 90° displaced in phase with respect to the voltage appearing across the resistor R at reference time zero when oscillation is initiated, the separate components of sine and cosine voltages are produced and these are combined in the over-all impedance Z to produce an excitation voltage E thereacross which is applied to the analogy circuit.

While the above described method of producing the cosine voltages has been used and has been found practical for most purposes, certain operational inconveniences are experienced in the use of excitation systems embodying this method for producing the cosine voltages. One such inconvenience resides in the fact that it is not always feasible to obtain smooth variation of the taps along the inductors $2L$ or $4L$. Additionally, the current in each of the inductors $2L$ and $4L$ also flows through the resistor R and produces an unwanted sine component therein. One method for eliminating the sine component produced by the cosine current is to proportion the current in the cosine oscillator circuits at a much lower value than that of the adjacent sine circuit so that the amount of unwanted sine component will be minimized. Another method is to balance out the sine component in an electrically opposed section of the resistor R . Nevertheless, this is still difficult to accomplish accurately and the convenience of uniform variations and ready manual manipulation by observing the oscillograph during test setup periods is lost.

According to this invention one method for minimizing the above problems, as illustrated in Fig. 5, utilizes the resistance R for both the sine and cosine components. In this embodiment the sine circuits include the components $L4$, $C4$, $R4$ and $L3$, $C3$, $R3$ as in Figs. 1 and 3. These circuits will accordingly be understood from the discussion of Fig. 1. In this instance, however, in the cosine circuits, and with particular reference to the cosine circuit including components $C2$, $L2$ and $R2$, the inductor $L2$ is connected across the battery B by a synchronous switch $SS2$ during periods when the various oscillator circuits are being charged. The same applies to the inductor $L4$ appearing in the other oscillator circuit for producing cosine components of the opposite polarity which additionally includes the capacitor $C4$ and resistor $R4$. Inductor $L4$ is connected across the battery B by means of a synchronous switch $SS4$ during charging intervals. The resistors $2R$ and $3R$ in the charging circuits for capacitors $C1$ and $C3$ in the sine voltage oscillator circuits are again of relatively high magnitude to afford substantial isolation of the charging circuits for the sine voltage os-

cillator circuits when the synchronous switch $SS1$ is closed but the requirements for the resistors $1R$ and $4R$ are slightly different. It will be remembered that the internal impedance of the excitation circuits as viewed from the analogy circuit must be low to prevent interference with oscillation of the analogy circuit during periods when the excitation circuits are producing the voltage E . Thus, the inductors $L2$ and $L4$ must include only a relatively few turns of wire to meet this condition. As a consequence, a rather large current is required through these elements to produce the required ampere turns in the circuit. For this reason the resistors $1R$ and $4R$ in the respective cosine charging circuits must be kept small and to afford isolation of the charging circuits the synchronous switches $SS2$ and $SS4$ are provided to open the charging circuits during periods when the oscillator circuits are closed.

Each cosine oscillator circuit is provided with a synchronous switch, respectively designated $SS3$ and $SS5$ for the two circuits. The capacitors $C2$ and $C4$ in the respective cosine circuits normally block the passage of direct current. However, upon application of the battery to the cosine circuit for building up ampere turns on inductors $L2$ and $L4$, the direct current voltage is not constant but builds up exponentially. Such a current would be passed by the capacitors and in the event of a closed connection to the resistor R would permit a current flow through the circuit network including the resistor R which may have a spurious effect in the function of the analogy circuit. If it is found that the effect of the charging current circulating through resistor R during the charging cycle is of negligible importance, then of course the synchronous switches $SS3$ and $SS5$ may be eliminated from the cosine circuits. In practice all synchronous switches are arranged along a common shaft with means being provided for adjusting the switch segments angularly about the shaft to effect any desired angular relation therebetween and means also being provided for individual adjustment of the brushes so that the on-off cycles of the switches can be adjusted to provide the desired switching characteristics.

In view of the fact that the inductors $L2$ and $L4$ are of low impedance since they have a relatively few number of turns, it will be appreciated that a fairly heavy current drain upon the source will occur upon closure of the switches $SS2$ and $SS4$. Practical considerations may make it necessary therefore to provide each of the cosine charging circuits with a separate battery to provide the required charging current. However, a more practical approach to this problem appears in the preferred embodiment illustrated in Fig. 6.

In Fig. 6, the sine voltage oscillator circuits have been eliminated for the purpose of simplification. Here again the cosine voltage circuits embody, respectively, an inductor $L4$, capacitor $C4$, resistor $R4$ and capacitor $C2$, inductor $L2$ and resistor $R2$. However, in this instance the inductors are provided with additional exciting or primary windings $P1$ and $P2$, respectively, having a large number of turns of small wire so that the desired ampere turns can be induced on these coils $L1$ and $L2$ with a small drain from the power supply. Each of the paired coil assemblies $P1$, $L1$ and $P2$, $L2$, it will be appreciated, respectively function as mutual inductors or, in effect, a transformer assembly so that the ampere turns of the primary in each case are trans-

ferrered inductively to the secondary circuits including the coils or inductors L_1 and L_2 .

As illustrated, the charging circuit including the two primaries P_1 and P_2 is a series circuit including, the battery B , the resistor $1R$ which now may be of relatively large magnitude, the two primaries P_1 and P_2 and a synchronous switch SS . When the synchronous switch SS is closed as illustrated in the drawing, steady conditions are established with the cores of the mutual inductors excited but with no voltage on the capacitors C_1 and C_2 . When the synchronous switch opens the charging circuit at time equals zero, the ampere turns of the primary windings are instantly transferred inductively to their respective secondary windings L_1 and L_2 in the cosine voltage oscillator circuits. In other words, a current is initiated at its peak value at time equals zero producing a cosine damped term. The series connection of these exciting coils P_1 and P_2 avoids any coupling between the circuits through the exciting circuit after the commutator has opened. This makes possible the use of the convenient slide wire adjustment along the resistor R for determining the relative characteristics of the cosine voltages with only a moderate drain on the power supply. As in previous instances hereinbefore discussed the voltage appearing across the resistor R is applied to the analogy circuit.

The application of this electrical analogy computer in a particular problem is illustrated in Figs. 7 through 9 in which the problem is that of determining the transient torque on the turbine generator shaft illustrated in Fig. 7 when the generator is synchronized out of phase. In this problem the generator is given an inertia value I_1 , the turbine an inertia value I_2 and the shaft a spring constant K all as illustrated in Fig. 7.

The torque developed in the rotor during synchronizing takes the form

$$T = Ae^{-\lambda t} - Be^{-\alpha t} \cos \omega t + Ce^{-\gamma t} \sin \omega t \quad (1)$$

where A , B , and C are functions of the angle of synchronizing, where λ , α and γ are decrement factors. This torque acts on the mechanical system consisting of the generator rotor, the generator, the turbine shaft and the turbine.

The equations for dynamic equilibrium of the mechanical system are given by

$$T = I_1 \frac{d^2\theta_1}{dt^2} + K(\theta_1 - \theta_2) \quad (2)$$

and

$$O = I_2 \frac{d^2\theta_2}{dt^2} + K(\theta_2 - \theta_1) \quad (3)$$

where

T =Input torque to the generator rotor
 I_1 =Inertia constant of the generator rotor
 I_2 =Inertia constant of the turbine rotor
 θ_1 =Angular displacement of the generator rotor relative to synchronous angular displacement
 θ_2 =Angular displacement of the turbine rotor relative to synchronous angular displacement
 K =Spring constant of shaft connecting the generator and turbine

If a mass-inductance analogy is used, voltage will correspond to torque, current to velocity, and charge to displacement. A simple excitation circuit which will produce voltage compo-

nents corresponding to the terms of the torque Equation (1) is shown in Figure 9.

The electrical analogy for the mechanical system is also shown in Fig. 9. The correspondence between the electrical analogy network of Fig. 9 and the mechanical system can be readily seen by writing the equations for dynamic equilibrium in terms of voltage and charge for the analogy network.

$$e = L_1 \frac{d^2q_1}{dt^2} + \frac{1}{c}(q_1 - q_2) \quad (4)$$

$$O = L_2 \frac{d^2q_2}{dt^2} + \frac{1}{c}(q_2 - q_1) \quad (5)$$

Note the similarity between Equations (2) and (4), and (3) and (5). The second term in Equations (4) and (5) represents the voltage drop across the capacitor C_1 , and since voltage is analogous to torque, gives directly the torque developed in the shaft.

The torque T given in Equation (1) represents the forcing function which excites the mechanical system. This may be written as a voltage E which is illustrated in the drawing as the voltage or forcing function which excites the electrical system and this voltage is to be produced across the resistor R forming a part of the excitation circuit. The characteristics of the separate voltages represented in the equation for the voltage shown are illustrated in Fig. 8 in which the ordinate represents voltage and the abscissa time. As is apparent from the form of the mathematical expressions defining each of the voltages, these voltages are exponentially damped. The first voltage, namely $Ae^{-\lambda t}$ is a unidirectional component which is decreasing exponentially. This is illustrated by the graph so designated in Fig. 8. The second voltage $Be^{-\alpha t} \cos \omega t$ may be considered as a fundamental frequency and of a sense relatively negative to that of the unidirectional component. This is the cosine term and accordingly is 90° displaced in phase from that of the component designated $Ce^{-\gamma t} \sin \omega t$ which is the third voltage. The addition of these curves represents the voltage E which is applied to the analogy network. The three circuits for producing the voltages are illustrated in the excitation network of Fig. 9 wherein for an instantaneous condition each of the voltages is designated according to the expression appearing in the voltage equation. The unidirectional damped term is produced in the circuit including a capacitor C_1 and resistor $1R$. The cosine term is produced in the circuit including the secondary winding S_3 of the transformer T_3 , the capacitor C_3 and resistor R_3 while the sine voltage is produced in the circuit including capacitor C_2 , inductor L_2 and resistor R_2 . The power supply in this instance for the charging circuits is designated as a block labeled PS . For this particular problem the power supply may be any suitable source of unidirectional voltage. The charging current for the damped unidirectional voltage circuit and for the sine voltage circuit is applied, respectively, across capacitors C_1 and C_2 . These charging circuits respectively include the resistors $1R$ and $2R$ which serve to isolate the charging circuits when the synchronous switch SS_1 has closed the oscillating circuits. The charging circuit for the cosine voltage circuit includes a synchronous switch SS_2 , the primary P_3 of the mutual inductor T_3 and the resistor $3R$ in a series loop across the power supply PS . As discussed in connection with Fig. 6, the inductor or secondary winding S_3 forming

a part of the cosine voltage oscillating circuit has but a few turns of wire whereas the primary P3 of the mutual inductor T3 has a large number of turns of small wire so that the required ampere turns can be produced with a small charging current. Here also the synchronous switches SS1, SS2 and SS6 are connected together to effect opening and closing of the circuits of which they each form a part in suitable time phase relation. In the arrangement illustrated in the drawing, switch SS2 is closed, switch SS1 is open and switch SS6 is closed. Thus the oscillator circuits are open and charging currents are flowing. In the analogy circuit the discharge circuit established by switch SS6 completely removes energy from the analogy circuit. In the next instant switch SS2 opens, switch SS1 closes and switch SS6 opens. Switch SS2 opens the cosine charging circuit and SS1 completes the three oscillator circuits. Switch SS6 opens the discharge path in the analogy circuit. Thus simultaneously the three components of voltages shown in Fig. 8 are initiated. This corresponds to time zero in the graph of Fig. 8 and each of the element voltages as shown by the exponential terms in the equations are exponentially damped producing across the resistor R the excitation voltage E which is applied to the analogy circuit. The forces acting upon the shaft connecting the turbine and the generator appear as voltages across the capacitor C and are traced on the screen of a cathode ray oscilloscope CRO. Due to the cyclic operation of switches SS1 and SS2 in the excitation network, the excitation voltage E is repeatedly applied to the analogy network at sufficiently small intervals to produce a standing wave of shaft stress on the cathode ray oscilloscope where it may be leisurely studied or photographed for the purpose of future record and the switch SS6 completely removes energy from the analogy circuit in the interval between excitation applications thereto.

It will also be appreciated from a study of the excitation network of Fig. 9 that the manner in which the combination of the voltages of the three separate oscillator units is accomplished corresponds exactly to that indicated in the equation of the voltages. The cosine term is negative in the equation and in the excitation circuit is combined with the other two voltages in an opposite sense since the point of connection of the cosine circuit with the resistor R is on the opposite side of the common leg of the excitation circuit along the resistor R from the points of connection of the two remaining circuits. It will be noted that the common leg or branch includes the synchronous switch, one side of which is connected to the resistor R and the other side of which is connected to a common terminal of the power supply which applies a reference voltage to the synchronous switch tap on the resistor R. Thus, voltages appearing along resistor R are relatively positive or negative with respect to this point depending upon the point of application of the particular circuit producing such voltage.

Although this invention has been illustrated in connection with a single practical application, namely that of the turbine generator of Fig. 7, it will be appreciated that the teachings hereof are by no means limited to such an application and it is therefore intended that the foregoing disclosure shall be considered only as illustrative of the fundamental principles of this invention.

I claim as my invention:

1. In an electrical analyzer network having an

analogy circuit which is the electrical counterpart of a system to be analyzed, an excitation circuit for producing voltages representative of the quantities affecting the said system comprising, in combination, a transformer having a high impedance primary winding and a low impedance secondary winding, an oscillator circuit including said low impedance secondary winding, a charging circuit including said high impedance primary

5 winding and impedance means having a low impedance with respect to said analogy circuit for connecting said oscillator circuit and said analogy circuit.

2. In an electrical analyzer network having an analogy circuit which is the electrical counterpart of a system to be analyzed, an excitation circuit for producing voltages representative of the quantities affecting the said system comprising, in combination, mutual inductor means having primary and secondary windings, the primary winding having a higher number of turns than the secondary winding, a charging circuit including said primary winding, an oscillator circuit including said secondary winding, switching means for 20 opening and closing said charging circuit, and impedance means having a low impedance with respect to said analogy circuit for connecting said oscillator circuit and said analogy circuit.

3. In an electrical analyzer network having an analogy circuit which is the electrical counterpart of a system to be analyzed, an excitation circuit for producing voltages representative of the quantities affecting the said system comprising, in combination, mutual inductor means having primary and secondary windings, the primary winding having a higher number of turns than the secondary winding, a charging circuit including said primary winding, an oscillator circuit including said secondary winding, switching means in 35 each of the charging circuits and the oscillator circuit for alternately opening and closing the charging circuit and the oscillator circuit, and impedance means having a low impedance with respect to the analogy circuit for connecting said oscillator circuit and said analogy circuit.

4. In an electrical analyzer network having an analogy circuit which is the electrical counterpart of a system to be analyzed, an excitation circuit for producing voltages representative of the quantities affecting the said system comprising, in combination, mutual inductor means having primary and secondary windings, the primary winding having a higher number of turns than the secondary winding, a charging circuit including said primary winding, an oscillator circuit including said secondary winding, switching means for opening and closing the oscillator circuit, resistor means in the charging circuit, said resistor means being of sufficiently high resistance to effectively 55 isolate the charging circuit from the oscillator circuit when said switching means closes said oscillator circuit, and impedance means having a low impedance with respect to the impedance of said analogy circuit for connecting said oscillator circuit and said analogy circuit.

5. In an electrical analyzer network having an analogy circuit which is the electrical counterpart of a system to be analyzed, an excitation circuit for producing voltages representative of the quantities affecting the said system comprising, in combination, a plurality of mutual inductors each having primary and secondary windings, a charging circuit connecting said primary windings in series, a plurality of oscillator circuits each including a secondary winding of said mutual in-

ductors, impedance means connected with all of said oscillator circuits and having a low impedance with respect to said analogy circuit, said impedance means being constructed and arranged for connection to said analogy circuit, and circuit means connecting a point of said charging circuit with a common point in each oscillator circuit and a point of said impedance means for establishing a reference voltage in said impedance means.

6. In an electrical analyzer network having an analogy circuit which is the electrical counterpart of a system to be analyzed, an excitation circuit for producing voltages representative of the quantities affecting the said system comprising, in combination, a first electrical circuit including an inductor and a capacitor, mutual inductor means having a primary winding and a secondary winding, a second electrical circuit including said secondary winding and a capacitor, circuit means for simultaneously energizing said capacitor of said first electrical circuit and said primary winding, impedance means connecting said first and second electrical circuits, switching means for opening and closing said circuit means and said first and said second electrical circuits in predetermined time phase relation, said impedance means being constructed and arranged for connection to said analogy circuit.

7. In an electrical analogy type of computer, the combination of, an analogy circuit which is the counterpart of a system to be analyzed, mutual inductor means having a primary and a secondary winding, said primary winding having a greater number of turns than said secondary winding, an oscillator circuit including said secondary winding, circuit means connecting said oscillator circuit to said analogy circuit, and a charging circuit connected to said primary winding.

8. In an electrical analogy type of computer, the combination of, an analogy circuit which is the electrical counterpart of a system to be analyzed, mutual inductor means having a primary winding and a secondary winding, said primary winding having a greater number of turns than said secondary winding, an oscillator circuit including said secondary winding, circuit means connecting the oscillator circuit to said analogy circuit, a source of electrical energy, and a cyclically operated switch connecting said primary winding to said source of electrical energy.

9. In an electrical analogy type of computer, the combination of, an analogy circuit which is the electrical counterpart of a system to be analyzed, mutual inductor means having a primary and a secondary winding, said primary winding having a greater number of turns than said secondary winding, an oscillator circuit including said secondary winding, circuit means connecting said oscillator circuit to said analogy circuit, a charging circuit connected to said primary winding, and switching means for alternately opening and closing said charging circuit and said oscillator circuit.

10. An excitation network for producing cosine voltages comprising, in combination, inductor means, an oscillator circuit including said induct-

5 tor means, impedance means forming a part of said oscillator circuit and across which said cosine voltages appear, a charging circuit connected to said inductor means, and switching means for alternately opening and closing said charging circuit and said oscillator circuit.

11. An excitation circuit for producing cosine voltages, comprising, in combination, mutual inductor means having a primary and a secondary winding, said primary winding having a greater number of turns than said secondary winding, an oscillator circuit including said secondary winding, impedance means forming a part of said oscillator circuit and across which said cosine voltages appear, and charging circuit means for energizing said primary winding.

12. Apparatus as set forth in claim 11 in which said charging circuit means comprises a synchronous switch for intermittently opening and closing the charging circuit.

13. An excitation circuit for producing cosine voltages comprising, in combination, mutual inductor means having a primary and a secondary winding, said primary winding having a greater number of turns than said secondary winding, an oscillator circuit including said secondary winding, impedance means forming a part of said oscillator circuit and across which said cosine voltages appear, a charging circuit connected to said primary winding, and switching means for alternately opening and closing said charging circuit and said excitation circuit.

14. Circuit means for producing cosine voltages comprising, in combination, at least two mutual inductors each having a primary winding and a secondary winding, the primary windings of each mutual inductor having a greater number of turns than the secondary winding thereof, a pair of oscillator circuits, each including one of said secondary windings so that each secondary winding forms a part of an oscillator circuit, said oscillator circuits having a common circuit branch, impedance means connected with each of said oscillator circuits to form a part thereof, and charging circuit means connecting said primary windings in series, said cosine voltages appearing across said impedance means.

15. Apparatus as set forth in claim 14 in which said charging circuit comprises switching means for intermittently opening and closing the charging circuit.
